LLP(57) **CLAIM**

The ornamental design for a paper product dispenser, as shown and described.

DESCRIPTION

FIG. 1 is a perspective view of a paper product dispenser showing the new design.

FIG. 2 is a front elevation view thereof.

FIG. 3 is a rear elevation view thereof.

FIG. 4 is a side elevation view thereof, with the opposite side being a mirror image thereof.

FIG. 5 is a top plan view thereof; and,

FIG. 6 is a bottom plan view thereof.

The broken lines represent portions of the dispenser for environmental purposes only and form no part of the claimed design.
